United States Patent

Des. 236,731
Patented Sept. 9, 1975

236,731

EDUCATIONAL PLUG-IN BOARD

Charles G. Valentine, Stamford, Conn., assignor to
Xerox Corporation, Stamford, Conn.

Filed Apr. 27, 1973, Ser. No. 355,228

Term of patent 14 years

Int. Cl. D19—07

U.S. Cl. D19—59

The figure is a right perspective view of an educational plug-in board showing my new design.

The rear and undisclosed sides of the educational plug-in board are substantially plain and unornamented.

I claim:

The ornamental design for an educational plug-in board, substantially as shown and described.
